STARTER MOTOR-DRIVEN HYDRAULIC PUMP

John B. Parsons, Maumee, Ohio

Application February 18, 1952, Serial No. 272,009

14 Claims. (Cl. 103—38)

1
This invention relates to fluid pumping systems, but particularly to a hydraulic pump operatively driven by an engine starting motor.

An object is to produce an electric starter motor driven pump, which is so constructed and arranged that when the motor is used for engine starting purposes, the resistance of the pump is reduced to a minimum in a new and improved manner, the same motor being employed also for pump operation so that the motor can serve not only for engine starting purposes but also for pump operation.

Another object is to produce an electric motor driven hydraulic pump, means separate from the pump being employed to reduce the resistance of the pump to a minimum when the motor is used for a purpose other than driving the pump.

A further object is to produce a hydraulic pump and electric motor unit in which the pump is carried by the motor shaft, means being provided for automatically reducing the resistance afforded by the pump to a minimum when the motor is used for a purpose other than for operating a pump.

A still further object is to produce a hydraulic pump unit operatively connected to an engine starting motor and so interconnected therewith that when the motor is used for engine starting purposes, a control member on the pump is automatically shifted so that although the pump is driven by the motor when the latter is used for engine starting purposes, the pump resistance is reduced to a minimum, the arrangement being such that the motor can be employed for pump operation when not used for engine starting purposes.

A still further object is to produce a fluid pump which is efficient in operation, simple and inexpensive to produce and assemble, and has the novel features of construction, arrangement and operation hereinafter described.

Other objects reside in details of construction, arrangement and operation hereinafter described, and for purposes of illustration but not of limitation, an embodiment of the invention is shown on the accompanying drawings, in which

Figure 1 is a diagrammatic view of a hydraulic window regulator mechanism in which the hydraulic pump is directly connected to the shaft of the engine starting motor;

Figure 2 is an enlarged side elevation of the engine starting motor and hydraulic pump connected thereto, the latter being shown in vertical section;

Figure 3 is a top plan view of the starter motor and pump assembly shown in Figure 2;

2
Figure 4 is a side elevation partly in section of the hydraulic pump and associated parts showing the position of the control valve and connections when the starter motor is employed for engine cranking purposes;

Figure 5 is a view similar to Figure 4, showing the position the parts assume in the event that a pressure in excess of a predetermined maximum is encountered during the pumping operation causing the valve to be shifted against the pressure of the spring to allow by-passing of the liquid;

Figure 6 is a view similar to Figures 4 and 5, but showing the valve in the position assumed when the pump is used for pumping operations, the valve being shifted sufficiently to enable liquid under pressure to pass to the window regulator unit;

Figure 7 is a longitudinal sectional view substantially on the line 7—7 of Figure 4;

Figure 8 is a longitudinal sectional view substantially on the line 8—8 of Figure 5;

Figure 9 is a longitudinal sectional view substantially on the line 9—9 of Figure 5;

Figure 10 is an enlarged fragmentary sectional view showing the spring pressed ball relief valve adapted to serve as a safety release in the event that the main shiftable valve becomes stuck or otherwise inoperative;

Figure 11 is an alternate form of motor and pump assembly; and

Figure 12 is a fragmentary sectional view of an alternate connection between the motor shaft and pump rotor.

The illustrated embodiment of the invention comprises a window panel 10 for an automobile or other vehicle, to the lower edge of which is fixed a channel 11 from which depends a pair of retainers 12 having longitudinally extending guideways 13 in which studs 14 are slidably horizontally. The studs 14 are fixed respectively to the free ends of swinging arms 15 and 16, which are pivotally connected respectively to upright stanchions 17 and 18. The arms 15 and 16 are pivotally connected intermediate their ends so that by swinging movement of the arms in one direction, the window panel 10 is lowered into the door well (not shown) and by swinging movement in the opposite direction, the window panel is raised to close the conventional window opening, as will be readily understood.

The lower ends of the stanchions are connected to a horizontally disposed cross bar 19, which is suitably fixed to a rigid part of the automobile door or the like. The lower end of the stanchion 17 is fixedly connected by a pair of rivets 20

but the lower end of the stanchion 18 is pivotally connected by a single rivet 21, so that the latter can rock toward and away from the stanchion 17 during the swinging movement of the cross arms.

Connected to the cross arm 15 at one side of the pivotal connection between the cross arms is a piston rod 22, which has a piston 23 at its lower end vertically slidable within a cylinder 24. Closing the lower end of the cylinder 24 is a fitting 25 which in turn is connected to a compensating arm 26, one end of which is pivotally connected to the lower end portion of the stanchion 17, a rivet 27 providing a stop for the upward movement of the free end of the arm 26. Hooked against the compensating arm 26 are helically coiled springs 28, the upper ends of which are hooked over the cross arm 16 between the pivotal connection of the arms and the stanchions 18.

Within the lower portion of the cylinder 24 is a solenoid controlled valve 29, which is spring-seated and is adapted to be unseated upon energizing of the associated solenoid, thereby to admit liquid under pressure thereto through a tube 30, thus to force the piston 23 upwardly and swing the cross arm regulator in such manner as to raise the window panel 10. By energizing the solenoid without energizing the hydraulic pump or source of liquid pressure, the window is lowered by the coil springs 28, causing the liquid in the cylinder 24 to be forced therefrom through the tube 30 to the reservoir as will hereinafter appear. The solenoid is grounded at 31 and extending from the solenoid is a lead 32 extending to a control switch as will be hereinafter described.

The tube 30 extends to the high pressure side of a pump P, a tube 31 extending from the low pressure side of the pump to a liquid reservoir.

As will hereinafter more fully appear, the pump P is driven by an electric motor M, which constitutes the starting motor for an automobile engine, for example, for cranking the internal combustion engine.

Fixed to the housing of the starting motor M is a starting solenoid S, which when energized through a link 33 (Figure 2), rocks an operating arm 34 in a counterclockwise direction thereby to effect an operative driving connection between the motor M and the internal combustion engine. This mechanism forms no part of the present invention and is well known to those skilled in this art, so that further description and illustration are not deemed necessary.

As shown, the actuating arm 34 and link 33 are connected by a pin 35 and mounted thereon is a yoke arm 36, the free ends of which are pivoted on the pin 35 and the opposite end of which is connected to a rod 37, which is threaded at one end to project through an aperture in the end of the arm 36 where it is adjustably held in place by a pair of lock nuts 38. If desired, coil spring means may be interposed between the arm 36 and the rod 37 to afford a resilient lost motion connection therebetween. The outer end of the rod 37 is riveted to a depending arm 39, the lower end of which is apertured to ride freely over a cylindrical extension 40 of the control valve. An intermediate portion of the arm 39 is apertured to receive a stationary cylindrical pin 41 over which the arm slides. The outer end of the extension 40 is formed with an annular groove to receive the forked upper end of a leaf spring 41, the lower end of which is apertured

to receive an adjustable anchor screw 42a. As will hereinafter more fully appear, when the starting solenoid S is energized, the link 33 is forced inwardly or to the left of Figure 1, and, through the arm 36 and rod 37, the arm 39 is moved to the left or away from the pump P thereby sliding the cylindrical extension 40 of the control valve outwardly against the tension of the spring 41. In the latter position of the valve extension, the pump merely circulates liquid without performing work, thereby enabling the starting motor M to be used for engine cranking purposes with a minimum amount of resistance. When the cylindrical valve extension 40 is in its inward position, the pump can be operated to generate liquid pressure for window regulator operation.

The pump P comprises a pair of similar gears 42 and 43, which are in mesh with each other, the gear 42 being secured to the armature shaft 44 of the starting motor M. For conveniently securing the gear 42 to the shaft 44, the outer end of the shaft is formed with a socket 45. Extending radially from the socket 45 are openings 46 to receive steel balls 47. The outer end portion of the socket 45 is counterbored and tapped to receive a screw 48 which has a cylindrical extension terminating in a tapered end portion 49. The screw 48 is preferably magnetized to retain the balls in position for facilitating assembly. The parts are so proportioned that when the screw 48 is tightened in the socket, the tapered end portion 49 and cylindrical extension force the balls outwardly firmly embedding them in the metal of the gear 42 thus to effect a simple, efficient and easily effected driving connection between the armature 44 and the pump gear 42. The pump gear 43 rotates freely upon a post or axle 50, the outer end of which is tapped to receive the anchor screw 42a.

The pump housing is formed of an intermediate plate section 51 which, as shown on Figure 8, has cavities to receive the pump rotors 42 and 43, there being arcuate cavities 52 and 53 on opposite sides of the meshing portions of the pump rotors. A groove 54 communicates with the cavity 52 on one side of the housing section 51 and a groove 55 on the opposite side of the housing section 51 communicates with the upper portion of the cavity 53.

Fastened to the outer side of the housing section 51 is an end plate 56, which has a centrally disposed aperture for the reception of the armature shaft 44 and a substantially inverted L-shaped countersunk groove or cavity 57. In the upper portion of this cavity is an aperture 58 for the cylindrical extension 40 of the control valve and at the lower portion is a tapped hole 59 to which is connected the tube 31. In the lower portion of the end plate 56 is an aperture 60 to receive the rotor supporting post 50. This section is formed with a continuous groove 61 to receive a sealing ring or packing 62.

Closing the inner side of the central section 51 of the pump housing is an end plate 63, which is formed with a countersunk groove or cavity 64 which is generally of inverted L-shape. A continuous boundary groove 65 receives a packing ring 66 and formed centrally is an opening 67 through which the armature shaft 44 extends. At the lower end is an annular cavity 68 into which projects the inner end portion of the axle 50. Manifestly, by placing the end plates 56 and 63 on opposite sides of the intermediate or body portion 51, the cavities in the

respective plates will communicate respectively with the high and low pressure sides of the pump, taking in liquid through the opening 59 and delivering liquid under pressure to the cavities 64 and 54. Both of the cavities or grooves 64 and 57 communicate with the valve receiving opening 69 formed in a boss 70 on the intermediate or body section of the pump housing. On the outer side of the boss 70 is a centrally apertured part 71, which has a press fit within this section with the aperture thereof aligned with the aperture 69. When the parts are assembled, the control valve is slidable through these registering apertures, this valve having a cylindrical extension 40, an intermediate spool portion 72 and a radially bladed or fluted end portion 73 affording a series of fluid passages in a predetermined position of the valve.

The position shown in Figure 4 is the position in which the valve member is moved substantially to the left so that the fluted or bladed end portion 73 enables the liquid to circulate within the pump housing as shown by the arrows. In this position of the parts, it will be observed that the arm 39 has been moved to the left positively to move the valve to this position, this being the position the parts assume when the starting motor is used for engine starting or cranking purposes. In Figure 5, the valve is in the same position shown in Figure 4, but the vertical arm 39 is in its normal position against the outer wall of the pump housing. This is the position the valve assumes for regulating the maximum pressure. In other words, the pressure exerted by the spring 41 is predetermined and when that pressure is exceeded, the valve automatically moves to the left, overcoming the tension of the spring 41 and allowing the liquid to recirculate, thereby militating against damage to the parts operated by hydraulic pressure. In this connection, it may be mentioned that the anchor screw 42a can be adjusted to regulate the pressure exerted by the spring 41, the spring having a portion bearing against the pump housing so that the more the screw 42a is tightened, the greater pressure will be exerted by the spring 41.

Another position of the valve is illustrated in Figure 6 which is the operating position when liquid under pressure is forced past the bladed or fluted end of the valve to the tube 30, the latter being connected to the intermediate housing section 51 at the upper portion thereof, a channel 74 extending to the space between the ends of the apertured member 71 and the boss 70. In this position, the valve is moved to the left of Figure 6 by hydraulic pressure which is sufficient to overcome the tension exerted by the spring 41.

The other position of the valve member is the extreme right-hand position, which is shown on the drawing in Figure 2, and in which the spool portion 72 uncovers an outlet passage 74, thereby enabling liquid from the tube 30 to pass about the spool portion and through the cavities 57 and 55 to the outlet port 59 and thence to the reservoir through the tube 31. This latter position of the valve is the normal position assumed by the valve when the pump is idle.

A series of bolt and nut assemblies 75 secure together the parts of the pump housing which, as shown, is essentially supported by the end of the motor shaft 44. To hold the housing from turning, a bracket 76 is secured to the lower end of the pump housing and this bracket extends

to the end wall of the electric motor M, an aperture 77 in a flange of the bracket fitting over one of the heads 78 of the motor securing bolts. Thus it will be understood that the bracket 76 is not a supporting bracket but merely to co-operate with a motor bolt to hold the pump from turning movements.

Figure 10 shows a pressure relief valve in which a spring-tensioned ball valve 79 is disposed between a pressure passage 54a and an intake passage 55a. The tension exerted by the spring which normally seats the ball 79 is such that the ball valve 79 is normally seated. However, when a pressure is generated on the pressure side of the pump in excess of a predetermined maximum, such that the fluted end 73 of the slide valve should move to the position indicated in Figure 5, to serve as a relief, the ball check valve 79 may be substantially at this time unseated to afford an additional precautionary or safety feature. The pressure relief valve 79 ordinarily will function only in the event that the main slide valve becomes stuck for one reason or another. Under ordinary circumstances, it is not contemplated that the pressure relief valve 79 will function.

The pump housing is maintained in spaced relation from the end wall of the starter motor M by a sleeve 80, a felt packing 81 being interposed between the end of the sleeve and an end plate 82 of relatively thin sheet metal which abuts against the inner wall of the pump housing. A plate 83 abuts against the front or outer wall of the pump housing and assists in retaining the usual packing surrounding the rotary or shiftable parts in place, the plates 82 and 83 being retained in position by the bolt and nut assemblies 75.

As shown in Figure 1, a switch 84 is for the pose of energizing the starter motor M for engine cranking purposes, a lead *d* extending from the switch 84 to the starting solenoid S forming a part of the starter motor assembly. From the other terminal of the switch extends a lead *d'* which joins a lead *f* which connects with a storage battery *g* and also extends to a binding post on the starter solenoid S. A branch *h* from the lead *f* extends to a relay 85 for the motor M, the relay 85 being also connected by a branch lead *i* to a lead *k* which provides a connection between the starter motor M and the solenoid S. Manifestly, by actuating the switch 84, not only is the starter solenoid S energized to effect cranking engagement with the internal combustion engine (not shown) of the vehicle, but also the starter motor M is energized. As above explained, when the starter solenoid S is energized, the control valve of the pump moves to the position shown in Figure 4, allowing the motor M to operate with a minimum of resistance afforded by the operation of the hydraulic pump.

For operating the window regulator mechanism, a switch 86 is employed, this switch having three poles from one of which extends a lead *b* to the motor relay 85. From another pole of the switch 86 extends a lead *a* which joins the lead *f* extending to the battery *g*, relay 85 and starter motor solenoid S, as above described. A third lead *c* extends from the remaining pole of the switch 86 to the solenoid of the solenoid valve assembly 25 which is associated with the piston receiving cylinder 24 of the regulator assembly.

From the above, it will be understood that by actuation of the switch 86 in one direction, the leads *c* and *f* are electrically connected, there concomitantly to energize the starter motor M as well as the solenoid associated with the solenoid

valve assembly 25. This enables the hydraulic gear motor to be operated to force liquid under pressure through the tube 30 past the solenoid valve assembly 25 for driving the piston 23 upwardly with respect to the cylinder 24 and thus actuate the regulator arms for raising or closing the window. Upon release of the switch 86 and its return to normal position, the liquid within the cylinder 24 will retain the piston in the position of adjustment. In the event that the switch is retained in its "on" position after the window 10 has been moved to its closed or fully raised position, the pressure built up by the pump will force the fluted end portion 73 of the valve to the position shown on Figure 5, so that the liquid can then merely circulate without performing useful work, such movement of the valve occurring after the pressure overcomes the force of the spring 41. However, in the event that this valve structure becomes stuck for any reason, then the pressure release valve 79 will be unseated to relieve the pressure generated by the pump.

When the switch 86 is moved in the opposite direction to that above described, the leads c and f alone are electrically connected, thereby to energize the solenoid valve assembly 25 to effect opening of the valve and enable the coil springs 28 to pull the cross arm regulator as well as the piston 23 downwardly, thereby to effect lowering of the window 10. This movement of the piston forces the liquid from the cylinder 24 back to the reservoir through the tube 30, and past the reduced neck 72 of the control valve and to the reservoir through the tube 31. Upon release of the switch 86, it will return to an intermediate or neutral position. A suitable switch for this purpose is shown and described in my United States Patent 2,446,141, dated July 27, 1948.

The form of the invention shown on Figure 11 is similar to that above described except for the connections to the motor shaft and to the solenoid actuated yoke. In this instance, the starter motor shaft 44a does not extend much beyond the end of the motor casing and is formed with a tapered socket 88 terminating in a tapped portion 89. Fitting into the socket 88 is the tapered projecting end portion 90 of a separate pump shaft 91 which terminates in a threaded end to engage the threads of the tapped portion 89. The pump rotor 42a has a keyway 92 to receive a key 93 in the shaft 91. One advantage of this structure is that it enables the pump to be separate from the starting motor and can be used and mounted elsewhere since it is a complete unit in itself and is equipped with its own shaft.

Another feature shown in Figure 11 which differs from the above structure is the adjustable connection between the yoke 36 actuated by the starter solenoid. In this case, the valve operating arm 39a has a vertical portion, upwardly and forwardly inclined, which is integral with a terminal portion having elongate slots for adjustably receiving bolts 94. The bolts 94 extend through apertures in an angle arm 95 which is riveted to the yoke. The bolts 94 engage threaded holes in a nut plate 96. This structure enables adjustment of the valve arm 39a relative to the yoke to be conveniently effected.

Figure 12 illustrates an alternate connection between the starter motor shaft 44 shown in Figure 2 and the pump rotor 42. In this instance, the screw 48a has a flat end 97 to bear against a relatively large ball 47a which in turn bears against the two smaller balls 47b. When the screw is tightened, the ball 47a forces the balls 75

47b outwardly in a radial direction into firm intimate engagement with the pump rotor 42, thereby creating a simple and effective driving connection.

From the above description, it will be apparent that I have produced an exceedingly simple and efficient starter motor driven pump, the entire assembly of which is carried by an extension of the motor shaft, thus dispensing with the necessity of a separate motor for driving the pump. The arrangement is such that when the motor is employed for engine cranking purposes, the pump is automatically rendered ineffective, the pump operating in the usual manner but the liquid merely circulating from the pressure side to the intake side. Thus the resistance afforded by the pump is reduced to a minimum and is such as to cause no appreciable load on the starter motor. It will further be manifest that the operation of the starter motor solenoid by which the starter motor and engine is effected, effects the shifting of the pump control valve in an extremely simple manner, thus positively rendering the pump ineffective at the time the electric motor is employed for engine cranking purposes.

It is to be understood that numerous changes in details of construction, arrangement and operation may be effected without departing from the spirit of the invention especially as defined in the appended claims.

What I claim is:

1. A device of the class described, comprising an engine starting motor, a fluid pump connected to be driven by said motor, a valve in said pump for controlling fluid flow having a portion projecting exteriorly of the pump, said valve having one position enabling fluid under pressure to be forced from the pump and a second position enabling relatively free fluid flow, and an operator engaging said projecting portion of the valve for actuating same to said second position when the motor is used for engine starting purposes thereby to reduce the pump resistance to a minimum.

2. A device of the class described, comprising an engine starting motor, a fluid pump connected to be driven by said motor, a valve in said pump for controlling fluid flow having a portion projecting exteriorly of the pump, said valve having one position enabling fluid under pressure to be forced from the pump and a second position enabling relatively free fluid flow, an operator engaging said projecting portion of the valve for actuating same to said second position when the motor is used for engine starting purposes thereby to reduce the pump resistance to a minimum, and means for automatically rendering said operator effective.

3. The combination of an electric motor, mechanism for operatively connecting said motor to an internal combustion engine for cranking same, a hydraulic pump carried and driven by the shaft of said motor, a control valve for said pump movable to a position enabling free circulation of the liquid handled by the pump, and an operative connection between said control valve and said mechanism for automatically moving the former to said free circulation position when the motor is employed for engine cranking purposes.

4. The combination of an electric motor, mechanism for operatively connecting said motor to an internal combustion engine for cranking same, said mechanism including a solenoid, and an actuating member responsive to said solenoid, a hydraulic pump carried and driven by the shaft of said motor, a control valve for said pump movable to a position enabling free circulation of the

liquid handled by the pump, and an operative connection between said control valve and said solenoid for automatically moving the former to said free circulation position when the motor is employed for engine cranking purposes.

5. The combination of an electric motor, mechanism for operatively connecting said motor to an internal combustion engine for cranking same, a hydraulic pump carried and driven by the shaft of said motor, a control valve for said pump movable to a position enabling free circulation of the liquid handled by the pump, an operative connection between said control valve and said mechanism for automatically moving the former to said free circulation position when the motor is employed for engine cranking purposes, and resilient means for moving said control valve from said free circulation position.

6. A device of the class described, comprising an electric motor for engine cranking purposes, a hydraulic pump connected to be driven by said motor, a rectilinearly shiftable spring-tensioned valve normally disposed in an operative position enabling liquid under pressure to be forced from the pressure side of the pump, said valve being shiftable to a position to enable relatively free circulation of liquid from the pressure to the intake side of the pump, and an operator outside of and separate from the pump for actuating said valve to said latter position.

7. A device of the class described, comprising an electric motor for engine cranking purposes, a hydraulic pump connected to be driven by said motor, a rectilinearly shiftable spring-tensioned valve normally disposed in an operative position enabling liquid under pressure to be forced from the pressure side of the pump, said valve being shiftable to a position to enable relatively free circulation of liquid from the pressure to the intake side of the pump, an extension on said valve disposed outside of the pump, and an operator outside of and separate from the pump and engaging said extension for actuating said valve to said latter position.

8. A device of the class described, comprising an electric motor for engine cranking purposes, electrically operated starter mechanism for operatively coupling the motor to the engine and embodying a translatorily movable part, a hydraulic pump connected to be driven by said motor, a rectilinearly shiftable spring-tensioned valve normally disposed in an operative position enabling liquid under pressure to be forced from the pressure side of the pump, said valve being shiftable to a position to enable relatively free circulation of liquid from the pressure to the intake side of the pump, an extension on said valve disposed outside of the pump, and an operator responsive to movement of said movable part disposed outside of and separate from the pump and engaging said extension for actuating said valve to said latter position.

9. The organization as claimed in claim 8, in which the spring tensioning the valve assists in returning the translatorily movable part to normal position when the starter mechanism is de-energized.

10. The organization as claimed in claim 7, comprising a lost motion connection between the valve and the operator enabling normal operation of the valve when the pump is operated for pumping purposes.

11. The combination of an electric engine starting motor, electrically operated starting mechanism including a solenoid and a rockable arm actuated by the solenoid, a fluid pump suspended on and operatively connected to the motor shaft, a control slide valve for the pump movable in one direction automatically in response to fluid pressure, an extension on said valve disposed outside of the pump, a spring urging said valve to normal pumping position, arm means engaging said valve extension for enabling valve movement freely and independently thereof, said arm means being connected to said valve extension for moving same against the tension of said spring to a position enabling free fluid circulation from one side to the other, and link means connecting said arm means to said rockable arm.

12. A fluid pump comprising a casing including 25 a flat central plate and side plates on opposite sides of and closing said central plate, rotor apertures in said central plate, interengaging pump rotors in said apertures, shaft means for one rotor, an inlet and an outlet for the casing, the inlet communicating with the low pressure side of the pump rotors, cavities in said plates respectively, one cavity establishing communication between the high pressure side of the pump rotors and the outlet, and a transversely shiftable spring-tensioned valve controlling the fluid flow from said last cavity and the outlet, the other cavity providing communication between the outlet and the low pressure side of the pump rotors, said valve controlling fluid flow from the outlet to the inlet and also upon predetermined movement to enable fluid to by-pass from the high to the low pressure side of the pump rotors.

13. A fluid pump as claimed in claim 12, comprising an extension on the shiftable valve disposed outside of the casing, and actuating means engaging said extension.

14. A fluid pump as claimed in claim 12, comprising an extension on said shiftable valve disposed outside of the casing, and adjustable spring means engaging said extension for tensioning the valve.
